Specification for Design.

Patented June 10, 1919.

Application filed January 30, 1919. Serial No. 274,147. Term of patent 14 years.

To all whom it may concern:

Be it known that I, MARK C. COSGRAY, a citizen of the United States, residing at Sandusky, in the county of Erie and State of Ohio, have invented a new, original, and ornamental Design for a Combined Engine Crank-Case and Dynamo-Shell, of which the following is a specification, reference being had to the accompanying drawing, forming a part thereof.

Figure 1 is a top plan view of the combined engine crank case and dynamo shell, showing my new design.

Fig. 2 is a side elevation; and

Fig. 3, an end elevation thereof.

I claim:

The ornamental design for a combined engine crank case and dynamo shell, substantially as shown.

MARK C. COSGRAY.
